IRONING MACHINE

Frederick M. Freis, Chicago, Ill., assignor to
Conlon Corporation, Cicero, Ill., a corporation
of Illinois

Original application August 29, 1941, Serial No.
408,703. Divided and this application October
19, 1942, Serial No. 462,538

4 Claims. (Cl. 38—61)

This invention relates to ironing machines and has to do with machines intended for domestic or home use having a rotating roll and a cooperating shoe movable to and from the roll.

My invention is directed to means for supporting the shoe and moving it to and from the roll, comprising quick release means and means for holding the shoe to the roll under spring pressure. More specifically, I provide a rockably mounted shoe operating shaft and associated shoe supporting means, in conjunction with means for quickly coupling and uncoupling the supporting means to and from the shaft, for movement of the shoe with the shaft to the roll or from the roll independently of the shaft. The coupling means comprises means for adjusting the spring pressure of the shoe and means assuring movement of the shoe away from the roll when the shoe supporting means is uncoupled from the shaft. Further objects and advantages of my invention will appear from the detail description.

In the drawings:

Figure 1 is a front view of an ironing machine embodying my invention;

Figure 2 is a back view of the machine of Figure 1, with the shoe cover removed; and

Figure 3 is an outer end view, on an enlarged scale of the gear housing and roll and shoe and associated parts, certain parts being partly broken away and certain other parts being shown in section.

This application is a division of my copending application for Ironing machine, Serial No. 408,703, filed August 29, 1941, which has matured into Patent No. 2,346,374, issued April 11, 1944. My instant invention is directed particularly to those features having to do with the mounting and operation of the shoe, to an understanding of which a detailed description of the other features of the machine is not essential. Accordingly, a brief description of the machine as a whole, with a detailed description of the shoe supporting and operating means of my instant invention, will suffice.

The ironing machine shown in Figures 1 and 2 comprises a base 40 conveniently formed of sheet metal and rectangular in plan and provided with rubber bumpers 41, a gear housing 42 bolted or otherwise suitably secured to base 40 adjacent one end thereof and extending upward therefrom, a roll 43 extending from gear housing 42 inward over base 40, and a shoe 44 mounted in back of roll 43 cooperating therewith

and movable to and from the roll. Roll 43 comprises an inner cylinder 45, conveniently formed of sheet metal, and a pad 46 mounted upon cylinder 45 in a known manner.

5 The roll 43 is driven from a suitable motor (not shown) housed therein, by means of appropriate gearing and control means (not shown) within gear housing 42, under control of rod 103 provided at its forward end with button 106, and the control member comprising knob 131 and shank 132 extending therefrom into a sheet metal casing 105 secured to and enclosing gear housing 42. A shoe operating arm 102 is disposed within the casing 105 and extends generally forwardly and upwardly therein. This arm 102 is swung upward and downward by suitable motor operated means (not shown) within casing 105, responsive to movement of knob 131 from its lower position shown in Figure 20 3 to an upper position and vice versa. The means for rotatably supporting the roll 43 and driving it, and for operating the shoe operating arm 102, and the associated controls, are fully disclosed in my above identified copending application and need not be described in greater detail here. So far as my instant invention is concerned, the roll 43 may be mounted and driven in any suitable known manner, any suitable known means may be provided for imparting 25 swinging movement to shoe operating arm 102 an appropriate distance in either direction, and any suitable known means for controlling operation of the roll 43 and of the shoe operating arm 102 may be provided. Suffice it to state that roll 43 is driven in a suitable manner and power means is provided for swinging shoe operating arm 102 a proper distance in either direction and then stopping it, there being suitable means provided for controlling operation of the roll 43 and of the shoe operating arm 102.

30 Shoe operating arm 102 is mounted at its rearward end on the outer end of a tubular shoe shaft 110 rockably mounted in a sleeve 111 formed integrally with the gear housing 42, shaft 110 being confined against endwise movement by stop collars 112 and 113 suitably secured thereon and contacting the ends of sleeve 111. A flanged hub 114, shown in Figures 2 and 3, is secured on the outer end portion of shaft 110 and arm 102 is secured to flange 115 of hub 114 in a suitable manner, conveniently by means of a screw 116. It will be seen that when shoe operating arm 102 is swung upward about the axis of shaft 110, in a clockwise direction as viewed in Figure 3, shaft 110 is turned clockwise for moving shoe

44 rearward away from roll 43, and when arm 102 is swung downward into its lowered position shown in Figure 3 shaft 102 is turned counterclockwise, as viewed in Figure 3, for moving the shoe to the roll into cooperating relation thereto.

Shoe shaft 110 extends inwardly above base 40 to about the mid-length of the shoe 44. A coupling arm 150 is secured on the inner end of shaft 110 and extends rearwardly therefrom, this arm being slotted from its rearward end. A shoe supporting arm 151, comprising two plates 152 (Figure 2), is loosely mounted on shaft 110 and straddles arm 150. At their rearward lower portions the plates 152 are secured together by a spacer 153 and a block 154, disposed between plates 152, is pivotally mounted therein below coupling arm 150, by means of associated studs 155. Adjacent their upper end plates 152 are secured together by a U-shaped bridge member 156, the arms of which are spot welded or otherwise suitably secured to plates 152. Bridge member 156 carries a rearwardly opening spring clip 157 of known type, secured thereto in a suitable manner and disposed to receive the upper portion of a release rod 158 provided at its upper end with a knob 159. The lower portion of rod 158 is threaded and screws through block 154. A thimble 160 is loosely mounted on rod 158 for movement lengthwise thereof, downward movement of this thimble being limited by a pin 161 secured through rod 158 and disposed within a recess 162 extending from the lower end of thimble 160. At its upper end, thimble 160 is recessed to provide a seat for the lower end of a coil compression spring 163, disposed about rod 158 and confined between thimble 160 and an inverted cup member 164 mounted on rod 158 and confined against upward movement thereon, by a pin 165 secured through the rod. The lower portion of thimble 160 is rounded as shown in Figure 3, to facilitate movement thereof onto the upper face of arm 150 when rod 158 is swung forwardly into its coupling position shown in Figure 3, in which position of the rod spring 163 is under compression.

The shoe 44 is of known type and is provided with a sheet metal cover 166, providing with the shoe a housing for enclosing the heating elements and associated parts. A channel clamping bar 167 is bolted or otherwise suitably secured to the back of shoe 44 at the mid-portion thereof and has secured thereto, by welding or in any other suitable manner, two spaced ears 168. A pin 169 extends through the upper forward portions of plates 152 and through ears 168, providing a pivotal connection between shoe 44 and shoe supporting arm 151, to which arm the shoe is thus connected for movement therewith to and from the roll 43.

A coil tension spring 170 is attached at its upper end to pin 169, conveniently by being hooked thereto, the lower end of this spring being hooked through a web element 171 formed integrally with the coupling arm 150. Since the line of pull of spring 170 is in back of shaft 110, this spring tends to swing the shoe supporting arm 151 rearward and downward, assuring proper contact of thimble 160 with coupling arm 150, when rod 158 is swung forward into coupling position.

Normally, rod 158 remains in its coupling position shown in Figure 3, thus coupling shoe supporting arm 151 to shaft 110 for movement therewith. When shoe operating arm 102 is swung upward, the shoe supporting arm 151 is moved

downward and rearward so as to move shoe 44 away from roll 43, and, when arm 102 is swung downward, shoe supporting arm 151 is swung forward moving the shoe to the roll into cooperating relation therewith, and spring 163 is placed under compression holding the shoe to the roll under spring pressure. In order quickly to release the shoe from the roll, rod 158 is moved rearwardly as to disengage thimble 160 from arm 150, spacer 153 limiting this rearward movement of rod 158. When the release rod 158 has been thus disengaged from arm 150, tension spring 170 swings shoe supporting arm 151 rearward and downward moving the shoe away from the roll. It will be understood that spring 163 is considerably heavier than tension spring 170 and that the latter does not objectionably interfere with the function of spring 163 in holding the shoe to the roll under spring pressure.

When the shoe 44 is in cooperating relation to the roll, as shown in Figure 3, it may be quickly released from shaft 110 by swinging release rod 158 rearward, as above explained. In order to recouple the shoe supporting arm 151 to shoe operating shaft 110, release rod 158 is swung forward into the slot of arm 150 so as to dispose thimble 160 above and in contact with the latter arm. As will be clear from the drawings, release rod 158, including knob 159, extends above shoe 44 and is accessible from in front of the machine for effecting the uncoupling and coupling operations referred to. By screwing release rod 158 through block 154, the compression of spring 163 may be varied. The release rod 158 thus provides quick acting and readily accessible means for coupling and uncoupling the shoe 44 to and from the shoe operating shaft 110, and also provides readily accessible means for adjusting the spring pressure exerted upon shoe 44 when the latter is in cooperating relation to roll 43.

As previously stated, the shoe 44 is of known construction and preferably heated by electrical resistance elements having an associated thermostat 173 (Figure 2), to which and the resistance element or elements, as the case may be, current is supplied by means of a suitable cord or cable 174 lead through the tubular shaft 110 at a point within the sheet metal casing 105. The latter is provided with a flanged removable cover plate 175 and provides a housing for the outer end portion of shaft 110 and associated parts. Conveniently the cable or cord 174 is provided at its free end with a plug cap 176 of known type, or any other suitable means may be provided, for connecting the cable to a source of electric current.

It will be understood that various changes in construction and arrangement of parts of my invention may be resorted to without departing from the field and scope thereof, and I intend to include all such variations, as fall within the scope of the appended claims, in this application in which the preferred form only of my invention has been disclosed.

I claim:

1. In an ironing machine, a rotating roll and a cooperating shoe, a rockably mounted shoe shaft in back of said roll, a coupling arm secured on said shaft extending rearward therefrom and provided with an open ended slot, a shoe supporting arm extending upward from said shaft loose thereon, means connecting said shoe to said supporting arm for movement therewith, a release rod having pivoted and screw con-

nections to said supporting arm extending upwardly of the latter and movable about its pivot into and out of the slot of said coupling arm, and means carried by said rod cooperating with said slotted arm for coupling said supporting arm to said slotted arm for movement therewith and for uncoupling said supporting arm from said slotted arm for independent movement away from said roll, said means comprising means for exerting spring pressure upon said shoe when the latter is in cooperating relation to said roll and for varying the effective force of said pressure by threading said rod through said screw connection.

2. In an ironing machine, a rotating roll and a cooperating shoe, a rockably mounted shoe shaft in back of said shoe, a coupling arm secured on said shaft extending rearward therefrom and provided with a slot opening through its rearward end, a shoe supporting arm extending upward from said shaft loose thereon, means connecting said shoe to said supporting arm for movement therewith, a block pivoted on said supporting arm, a release rod threaded through said block movable about the pivot thereof into and out of the slot of said coupling arm, a thimble loose on said rod disposed to bear on the upper face of said slotted arm when said rod is disposed in said slot, means on said rod yieldingly urging said thimble downward, and means for rocking said shaft.

3. In an ironing machine, a rotating roll and a cooperating shoe, a rockably mounted shoe shaft in back of said shoe, a coupling arm secured on said shaft extending rearward therefrom and provided with a slot opening through its rearward end, a shoe supporting arm extending upward from said shaft loose thereon and straddling said slotted arm and extending downward therebelow, means connecting said shoe to said supporting arm for movement therewith, a

block pivoted in said supporting arm below said slotted arm, a release rod threaded through said block movable about the pivot thereof into and out of the slot of said coupling arm, a thimble 5 slidable on said rod disposed to bear on the upper face of said slotted arm when said rod is disposed in said slot, an abutment member on said rod above said thimble confined against upward movement, a compression spring on said rod confined between said thimble and said abutment member, and means for rocking said shaft.

4. In an ironing machine, a rotating roll and a cooperating shoe, a rockably mounted shoe shaft in back of said shoe, a coupling arm secured 10 on said shaft extending rearward therefrom and provided with a slot opening through its rearward end, a shoe supporting arm extending upward from said shaft loose thereon and straddling said slotted arm and extending downward 15 therebelow, means connecting said shoe to said supporting arm for movement therewith, a block pivoted in said supporting arm below said slotted arm and in back of said shaft, a release rod threaded through said block movable about 20 the pivot thereof into and out of the slot of said coupling arm, a thimble slidable on said rod having limited downward movement thereon and disposed to bear on the upper face of said slotted arm when said rod is disposed in said slot, an abutment member on said rod above said thimble confined against upward movement, a compression spring on said rod confined between 25 said thimble and said abutment member, means for rocking said shaft, means yieldingly urging 30 said supporting arm downward and rearward about said shaft in a direction to move said thimble toward said slotted arm, and means for releasably holding said rod in position disposed in the slot of said coupling arm.

40

FREDERICK M. FREIS.
